CLAIM

The ornamental design of a pet house, substantially as shown and described.

DESCRIPTION

FIG. 1 is a perspective view taken from the top, front and right side of a pet house showing our new design; FIG. 2 is a front elevational view thereof; FIG. 3 is a bottom plan view thereof; FIG. 4 is a rear elevational view thereof; FIG. 5 is a top plan view thereof; FIG. 6 is a left side elevational view thereof, the right side elevational view being a mirror image thereto; and FIG. 7 is a fragmentary elevational view taken on line VII—VII of FIG. 2.
